UNITED STATES PATENT OFFICE.

ADOLPH E. HERMAN, OF TERRE HAUTE, INDIANA.

DESIGN FOR A COACH-BODY.

SPECIFICATION forming part of Design No. 21,116, dated October 13, 1891.

Application filed September 16, 1891. Serial No. 405,897. Term of patent 7 years.

To all whom it may concern:

Be it known that I, ADOLPH E. HERMAN, a citizen of the United States, residing at Terre Haute, in the county of Vigo, State of Indiana, have invented and produced a new and useful Design for Coach-Bodies, of which the following is a specification.

The leading feature of my invention consists in the elongated shape of the coach-body, the top and back being formed in slightly-convex continuous lines, and the front bottom portion with the door being also formed slightly convex. The lower half of the coach-body presents a solid appearance, and the upper half is broken up by spaces forming windows.

The general design presents in side eleva-

tion an elongated body with five divisional lines or panels *a* extending vertically of the upper half of the coach-body, two of the panels forming the door-space. Wings project from the body in front of the doors near the bottom line thereof, forming a flaring end to the panels adjacent to the door-openings on the front.

I claim—

The design for a coach-body herein shown and described.

In testimony whereof I affix my signature in presence of two witnesses.

ADOLPH E. HERMAN.

Witnesses:

M. A. HERMAN,
CHAS. HEMMERLE.
